SHOE LAST

Sidney Kurlan, Rochester, N. Y., assignor to
George C. Clark, Beverly Hills, Calif.

Original application June 23, 1932, Serial No.
618,982. Divided and this application June 18,
1934, Serial No. 731,173

4 Claims. (Cl. 12—136)

The invention relates to shoe lasts and is a division of an application filed by me June 23, 1932, Serial No. 618,982.

The object of the present invention is to prove the construction of hollow metal lasts which are divided transversely into front and rear sections hinged together at their adjacent ends, more especially to improve the construction of the hinge joint for connecting the sections and to provide a simple, strong, practical, sturdy hinge joint composed of interfitting bearing lugs and bearing recesses presenting broad bearing surfaces to each other with the lugs provided with means for preventing lateral shifting of the sections.

A further object of the invention is to provide a hinge joint of this character having solid imperforate lugs adapted to eliminate entirely the transverse pivot ordinarily employed for connecting the front and rear sections of a last and provide an open unobstructed space between the bearing lugs to facilitate the installation and operation of locking means for locking the sections of the lugs in position for lasting operations.

It is also an object of the invention to provide the last sections with abutting shoulders located below the bearing lugs and recesses and adapted to support the rear or heel section of the last at the desired elevation and capable of being readily trimmed for effecting an adjustment of the rear section for providing the proper heel height.

With these and other objects in view, the invention consists in the construction and novel combination and arrangement of parts herein-after fully described, illustrated in the accompanying drawing and pointed out in the claims hereto appended, it being understood that various changes in the form, proportion and minor details of construction, within the scope of the claims, may be resorted to without departing from the spirit or sacrificing any of the advantages of the invention.

In the drawing:—

Figure 1 is a side elevation of a metal last constructed in accordance with this invention and showing the same after it has been turned in accordance with the method of the aforesaid application but prior to the removal of the terminal lugs.

Fig. 2 is a side elevation of the completed last.

Fig. 3 is a horizontal sectional view on the line 3—3 of Fig. 2.

In the accompanying drawing in which is illustrated the preferred embodiment of the in-

vention 1 designates a hollow metal sectional last preferably constructed of the magnesium alloy described in said application but the last may be made of any other suitable material.

As explained in the aforesaid application in 5 the manufacture of the last a magnesium alloy block is cast with terminal lugs or portions 2 and 3 which enable it to be held in a lathe and which are trimmed off after the last has been shaped in a shoe turning machine or profile machine the 10 same as a shoe last made of wood. In Fig. 1 of the drawing the last is shown after it has been turned and prior to the removal of the terminal lugs 2 and 3 while in Fig. 2 the terminal lugs have been trimmed off and the last completed. 15

The hollow metal shoe last is composed of hinged front and rear sections 4 and 5 which are formed by cutting the hollow block of magnesium transversely into the two sections 4 and 5 with bearing recesses 6 and bearing lugs 7 at the 20 lower portions of their adjacent ends to form a hinge joint or connection to enable the last to break in the usual manner. The bearing recesses 6 have wide transversely disposed bearing surfaces which are partially formed by webs or 25 flanges 6^a and 6^b projecting inwardly from the inner faces of the side walls of the hollow front last section 4. The side walls of the hollow rear last section 5 are thickened at their front ends at the said bearing lugs 7 to increase the length of 30 the lugs transversely of the last for providing wide bearing surfaces. The lugs are imperforate and are spaced apart to provide an entirely open space between the hinge joints at the opposite 35 sides of the last to facilitate installation and operation of suitable locking means for locking the sections in position for lasting operations in the use of the last.

The sections 4 and 5 are provided below the bearing recesses 6 and bearing lugs with abutting shoulders 8 and 9 which limit the swinging movement of the sections on each other in one direction and which support the heel portion of the rear section at the desired elevation when the sections are locked in operative position in the usual manner. 45

Any suitable means may, of course, be employed for locking the sections and for permitting the sections to break and the front section is provided at the inner faces of its side walls with 50 interior bosses 10 for the attachment of such locking means.

The recesses 6 and the lugs 7 form contacting bearing faces and the lugs which extend inward laterally beyond the bearing faces of the bearing 55

- 5 recesses and beyond the edges of the flanges 6^a and 6^b are provided at their inner ends with flanges 11 extending beyond the walls of the bearing recesses and engaging the said flanges 6^a and 6^b interiorly of the hollow front section 4 to prevent any relative lateral movement of the front and rear sections 4 and 5 . Instead of forming the front and rear sections from a single block it will be obvious that the sections 10 may if desired be cast separately to form a rough blank to be placed in a lathe for shaping the last.
- 15 When the last is removed from the lathe or other woodworking or last turning machine it is in the form illustrated in Fig. 1 of the drawing with the terminal portions or lugs 2 and 3 , after which these terminal portions or lugs are trimmed off and the last is completed in its finished form 20 as illustrated in Fig. 2 of the drawing. The sections 4 and 5 of the shoe last are rigidly locked in fixed relation to each other while the last is being shaped in a last turning machine by the means shown and described in the said application, the adjusting screw 18 of which appears 25 in Fig. 1 of the drawing. As this locking means does not constitute a portion of the present invention specific description and illustration thereof are deemed unnecessary in the present application.
- 30 Any style or form of last may be constructed in approximately the shape of a shoe last and then shaped to the exact form or style of shoe last desired and while it is preferred to make the last of the magnesium alloy of the said application other metals may be employed in the construction of the last. A magnesium alloy shoe 35 last is much lighter than aluminum and substantially as strong as mild steel and it is not affected by heat or dampness and can be applied 40 without fear of shrinkage, expansion and swelling or checking and it will preserve its specific contour and exact dimensions indefinitely, also it will be clear that with the hollow magnesium alloy shoe last a heating element may be provided interiorly of the last for applying heat to 45 the same, or the application of heat may be made to the last exteriorly thereof without injuring the last or in anywise affecting the contour and dimensions of the same.
- 50 What is claimed is:—
1. A shoe last comprising front and rear hollow sections provided at their adjacent ends with interfitting bearing recesses and bearing lugs presenting broad bearing surfaces, the section having the bearing recesses being provided at the inner faces of its side walls with laterally projecting flanges forming portions of the bearing surfaces of the recesses and increasing the area 55 of the same and the bearing lugs being solid and imperforate and spaced apart to provide an uninterrupted open space between the said inner ends of the lugs to facilitate the introduction and operation of locking means for locking the sections in position for use.
2. A metal shoe last comprising front and rear hollow sections provided at their adjacent ends with interfitting bearing recesses presenting relatively broad bearing surfaces, the section having the bearing recesses being provided at the inner faces of its side walls with laterally projecting flanges forming portions of the bearing surfaces of the recesses and increasing the area 10 of the same and the bearing lugs being solid and imperforate and spaced apart to provide a central uninterrupted open space between the bearing lugs to facilitate the introduction and operation of locking means for locking the sections 15 in operative position for lasting operations, the lugs being provided at their inner ends with flanges projecting laterally of the lugs and engaging the flanges of the bearing recesses and arranged to hold the sections of the last against 20 lateral shifting.
3. A metal shoe last comprising front and rear hollow sections provided at their adjacent ends with interfitting bearing recesses and bearing lugs presenting broad bearing surfaces, the bearing 25 lugs being solid and imperforate and spaced apart at their inner ends to provide an uninterrupted open space between the said inner ends of the lugs to facilitate the introduction and operation of locking means for locking the sections 30 in position for use, and bosses formed integral with the side walls of the front section of the last and located in advance of the bearing recesses and lugs for the attachment of locking means for holding the sections rigid with each 35 other for lasting operations.
4. A metal shoe last comprising front and rear hollow sections provided at their adjacent ends with interfitting bearing recesses presenting relatively broad bearing surfaces, the section having the bearing recesses being provided at the inner faces of its side walls with laterally projecting flanges forming portions of the bearing surfaces of the recesses and increasing the area 40 of the same and the bearing lugs being solid and imperforate and spaced apart to provide a central uninterrupted open space between the bearing lugs to facilitate the introduction and operation of locking means for locking the sections in operative position for lasting operations, the lugs being provided at their inner ends with flanges projecting laterally of the lugs and engaging the flanges of the bearing recesses and arranged to hold the sections of the last against 45 lateral shifting, and bosses formed integral with the side walls of the front section of the last and located in advance of the bearing recesses and lugs for the attachment of locking means for holding the sections rigid with each other for 50 lasting operations.

60 SIDNEY KURLAN.
